UNITED STATES PATENT OFFICE

1,986,632

CATHODE RAY TUBE OSCILLATOR

Clarence W. Hansell, Port Jefferson, N. Y., assignor to Radio Corporation of America, a corporation of Delaware

Application January 3, 1930, Serial No. 418,281

9 Claims. (CL. 250—36)

My present invention relates to oscillators, and, more particularly, to oscillator circuits embodying space discharge devices of novel construction, the oscillator circuits being such that 5 the output is much less affected by undesired emission variations, than the circuits now in common use.

In my United States Patent No. 1,850,104, granted March 22, 1932, on an application filed 10 October 18, 1929, there has been disclosed a method of, and means for eliminating tube noises in the final output of high frequency energy amplifiers, it being understood that such tube noises occur because of actual irregularities 15 in the rate of emission of electrons from the tube cathodes; the method disclosed permitting greater radio frequency amplification to be used so that smaller values of radio frequency energy could be amplified successfully. Briefly, my 20 above mentioned patent discloses an amplifier circuit which comprises an electron discharge tube including a cathode, a plurality of anodes electrostatically shielded from the cathode, the anodes being connected in such a manner that 25 variations in emission from the cathode result in equal and opposite variations in the anode output circuit whereby the disturbing anode currents balance out and no noise is present in the output of the amplifier.

Now, I have found that this novel cathode tube lends itself very satisfactorily to operation in an oscillator circuit, so that it is not necessary to supply an additional type of tube to be used 30 as an oscillator in equipment where an oscillator is required as well as amplifiers, as, for example, in a heterodyne or super-heterodyne type of radio receiver.

Accordingly, it is one of the main objects of the present invention to provide an oscillator 40 circuit which permits the use of the novel form of cathode ray tube so that a minimum number of types of tube may be employed in certain kinds of equipment, and the oscillation frequency of which circuit may be controlled by 45 piezo-electric means, a resonant long line, or an aperiodic, impedance matched line, or combinations of these.

Another important object of the invention is to provide an oscillatory circuit adapted to be 50 rendered stable with regard to its oscillation frequency, the frequency stabilizing means being automatic in its action.

Other objects of the invention are to improve 55 generally the efficiency of oscillation circuits embodying cathode ray tubes, and to, further, pro-

vide a tube which is durable and reliable in operation, possess a high power output, a minimum of undesired reaction between the electrodes of the anode circuit and the electrodes of the input circuit, and which may be readily arranged in a frequency stable oscillatory circuit.

The novel features which I believe to be characteristic of my invention are set forth in particularity in the appended claims. The invention itself, however, as to both its organization 10 and method of operation will best be understood by reference to the following description taken in connection with the drawing in which I have indicated diagrammatically several circuit organizations whereby my invention may be carried into effect.

In the drawing,

Fig. 1 diagrammatically shows an oscillatory circuit embodying the invention.

Fig. 2 shows an oscillation circuit employing 20 a modified form of frequency stabilizer.

Referring now to the accompanying drawing in which like reference characters indicate the same parts in the different figures, there is shown in Fig. 1, a cathode ray tube of the same construction as disclosed in my aforementioned Patent 25 No. 1,850,104, supra, wherein the tube is described in great detail. Accordingly, I will, in this application, confine myself to essentials necessary only for a clear understanding of the present 30 employment of the tube. The tube cathode 1 is heated by a source A, the resulting electron stream 20 therefrom, passing between a pair of elongated electrodes 13, 13'.

A pair of anodes 9, 9' are disposed within the 35 tube, and electrostatically shielded from the cathode and control electrodes by a screen grid electrode 10. The latter is supported by a metallic, cylindrical envelope 11, the envelope being affixed to a metallic disk-like support and shield 40 14. The anodes are energized from a source B, the positive terminal of the latter being connected to the anode circuit, the latter including the inductance 20' and the variable capacity 21 shunted across the latter, which circuit connects 45 the anodes in push-pull fashion.

A second metallic, cylindrical envelope 22 surrounds the control electrodes 13, 13', and is negatively biased by means of a lead 18 from the source D, the function of the envelope being to 50 concentrate the electronic stream 20 issuing from the cathode 1. The screen grid 10 is positively biased through a lead 19 and member 14, from a source E. The control electrodes 13' and 13 are connected in series through an inductance 31, 55

the midpoint of the latter being tapped and connected through a lead 32 to the negative terminal of source C, it being noted that the sources D, C, E, and B are connected and grounded between the positive terminal of source C and the negative terminal of source E.

In order to feed back energy from the output circuit to the input circuit the inductance 20' is coupled to the inductance 31. It will be noted that this inductive coupling will be the only source of feedback, inasmuch as there is no possibility of feedback occurring within the tube due to the electrostatic shield 10. By varying the condenser 21, it is of course, possible to vary the oscillation frequency of the circuit. A coil 40, connected to any useful load may be coupled to the inductance 20' for utilizing the oscillations set up in the anode circuit of the tube.

The tube, arranged as shown in Fig. 1, constitutes an initial source of oscillations. To stabilize its frequency piezo-electric crystal means, generally designated as 41, may be connected in the input circuit, in shunt with the inductance 31. The stabilizing action of the crystal is well known to those skilled in the art.

Again, the long line type of frequency control employing a resonant line may be employed. This type of control is shown and claimed in my application Serial No. 400,489 filed October 18, 30 1929, now Patent No. 1,945,546 granted February 6, 1934. I have therefore shown the resonant long line type of frequency control in Fig. 1, in diagrammatical manner, as comprising a pair of electrical conductors 50, 51 each of which has 35 one end connected to one side of the inductance 31. A shunting conductor 52, adjustable in the direction of the arrow, is adapted to vary the physical length of the two conductors. A capacity 53 should preferably be shunted across the inductance 31 for rendering the input circuit 40 more readily susceptible to resonance phenomena.

While the crystal control will ordinarily be employed independently of the resonant line control, they may be employed in combination, if desired. Briefly, the operation of the resonant long line type of frequency control is as follows: The long, resonant line 50, 51, 52 acts as a sharply tuned circuit having substantially uniformly distributed inductance and capacity. Standing waves are built up on the line giving it an equivalent input reactance which is dependent solely upon the frequency, the length of the line, and independent of any reaction caused by external 45 circuits or loads. These standing waves produced on the line, are applied to the oscillating tube for controlling the frequency of the latter. Thus, the long line acts as a very sharply tuned resonant circuit to pull the oscillator into step therewith.

Again, the line may be considered to act as a phase shifter, waves from the oscillator being sent over to the line to the far end and reflected back to the oscillator, arriving back with a phase 50 which shifts rapidly with change of frequency and which tends to modify the oscillator frequency to make zero difference in phase between the ingoing and reflected waves at the input end of the line. That is to say, the long line acts 55 to pull the oscillator into phase with its own oscillations whenever there is a shift in phase caused by a shift in the oscillator frequency.

The output from the anodes 9, 9' being connected, as shown, in push-pull manner, it therefore 70 results that the equal variations in the an-

ode currents due to the usual source of tube noise will balance out, and no noise will be transmitted with the useful signals.

In Fig. 2, I have shown an oscillatory circuit employing a cathode ray tube, as in Fig. 1, the circuit being modified, however, for frequency control by a long line of the aperiodic, impedance matched type. The latter type of control has been described, in detail, and claimed by J. L. Finch and J. W. Conklin in application Serial No. 363,660 filed on May 16, 1929.

In adapting this type of long line control to the present cathode ray tube oscillation circuit, the input and output circuits are tuned by the variable capacities 53 and 21 respectively.

As in Fig. 1, the anodes 9, 9' are connected in push-pull to the source B. The cathode is heated by source C, the latter also serving to negatively bias both control electrodes. The negative terminal of source C is connected through a resistance R, to the midpoint of the inductance 31, the latter being in series with the control electrodes 13, 13'. The resistance R is shunted by a radio frequency by-pass capacity 60.

A pair of series connected capacities 61, 62 are connected across the cathode and their midpoint grounded for by-passing radio frequency currents to ground so that no radio frequency voltage will appear on the cathode.

The source D negatively biases the envelope 22, the positive terminal of the source D being connected to ground, the positive terminal of the source C, and the negative terminal of source E also being grounded. The inductance 31 is adjustably tapped by two electric conductors 50, 51, as at 50', 51', on either side of the midpoint connection. The opposite terminals are connected to the anode inductance 20', as at 54, 55, through capacities 56 and 57, on either side of 40 the source B midpoint connection.

Briefly, the operation of this type of control is as follows: For the production of sustained oscillations by means of the cathode ray tube it will be necessary that the control electrodes 45 13 and 13' and anodes 9 and 9' fluctuate in potential 180 degrees out of phase for a desired frequency. In order to cause this phase relationship for the production of stable sustained oscillations, a long line is connected from the 50 points 54 and 55 in the output circuit of the tube to points 50' and 51' in the input circuit thereof.

By making the long line an odd number of 55 half wave lengths long at a desired frequency, or by making it an even number of half wave lengths long and reversing the connections at one end, it will be seen that potential variations occurring at points 54, 55 will appear on the control electrodes 13, 13' a certain period of time 60 later, because of the time required to travel over the lines 50, 51 so as to be opposite in phase to potential fluctuations occurring at points 54, 55. For any other frequency of potential fluctuations the lines 50, 51 will not be of the correct 65 length to give proper phase relationship, and hence, other frequencies will be discriminated against.

The energy of the frequency for which the 70 lines 50, 51 are made to give the proper phase relation for oscillation, may be regeneratively amplified to any desired extent by the suitable choice of the values for the electrical elements involved so that either regenerative amplification or sustained oscillations results. The anode 75

potential is kept from the control electrodes by means of the blocking condensers 56, 57. The output of the tube may be taken from an inductance 40 which is inductively coupled to the 5 output inductance 20', the coil 40 being connected to any utilizing circuit. In order to prevent reflection, the line 50 and 51 are tapped on inductance 31 at points which cause the lines to be terminated by an impedance R , in the form 10 of a resistance, corresponding in value to the surge, or characteristic impedance of the lines 50, 51. The exact frequency for which the circuit oscillates readily and with maximum efficiency and stability is obtained is adjusted by 15 varying the lengths of the line 51, 50.

While I have indicated and described several systems for carrying my invention into effect, it will be apparent to one skilled in the art that my invention is by no means limited to the particular organizations shown and described, but that many modifications in the circuit arrangements, as well as in the apparatus employed, may be made without departing from the scope of my invention as set forth in the appended claims. 20

25 In particular I wish to point out that the detail proportions and construction of the cathode ray tube and associated circuits shown will undoubtedly be modified by careful considerations of detailed design to permit of constructing the tube 30 with less practical difficulties.

What I claim is:

1. An apparatus for producing electrical oscillations comprising a cathode ray type of vacuum tube having a cathode, a plurality of control electrodes, and a plurality of anodes, means for suitably applying a negative potential on said control electrodes and a positive potential on said anodes with respect to said cathode, an input circuit connected to the control electrodes 35 and an output circuit connected to said anodes, both circuits being tuned to the frequency of the oscillations, means for regeneratively coupling the input and output circuits together externally of said tube, means for preventing feed-back 40 inside said tube, and means for stabilizing the frequency of the oscillations by coupling to the input circuit only of the oscillator a piezo-electric crystal oscillator.

2. An apparatus for producing electrical oscillations comprising a cathode ray type of vacuum tube having a plurality of control electrodes and a plurality of anodes, means for suitably applying direct current potentials to the control electrodes and anodes of the tube, input and output circuits each tuned to the frequency of the oscillations, means for regeneratively coupling the input and output circuits, and means independent of said output circuit comprising a sharply tuned resonant transmission line circuit on which stationary electromagnetic waves are allowed to develop coupled to the input circuit of said oscillator for stabilizing the frequency of the oscillations, and a utilization circuit coupled to said output circuit.

3. An apparatus for producing electrical oscillations comprising a cathode ray type of vacuum tube having a cathode, a plurality of control electrodes, and a plurality of anodes, means for applying a negative potential to said control electrodes and a positive potential to said anodes with respect to the cathode of said tube, input and output circuits tuned to the frequency of the oscillations connected to said control electrodes and said anodes, respectively, and means comprising a transmission line on

which standing waves are developed for regeneratively coupling the output and input circuits together whereby the frequency of the oscillations is held substantially constant.

4. In oscillation generating apparatus, a cathode ray electron discharge device having among the electrodes contained within its evacuated container an electron emitting cathode, a plurality of control electrodes and a plurality of anodes, an input circuit connected to the control electrodes and an output circuit connected to said anodes, said output circuit being tuned to the frequency of the oscillations, means for regeneratively coupling the input and output circuits together, an electromechanical vibrator 10 and a resonant transmission line coupled to the input circuit of said device for stabilizing the frequency of oscillations, said vibrator acting to overcome small variations in frequency and said resonant transmission line acting to overcome 15 greater variations in frequency.

5. In oscillation generating apparatus, a cathode ray electron discharge device having within an evacuated container an electron emitting cathode, a plurality of control electrodes 25 and a plurality of anodes, an input circuit for said control electrodes and an output circuit for said anodes, said output circuit being tuned to the frequency of oscillations, means comprising a long transmission line long relative to the 30 wave length of the working frequency for regeneratively coupling said input and output circuits together and for controlling the frequency of oscillations appearing in said input circuit.

6. In an oscillation generator, a cathode ray 35 electron discharge device having within an evacuated container a plurality of anodes, a plurality of control electrodes, and an electron emitting cathode, external means for coupling said anodes and control electrodes together, 40 means for preventing internal feed-back in said device, a crystal in circuit with the control electrodes of said device, and a tunable resonant circuit connected to the anodes of said device.

7. In an oscillation generator, a cathode ray 45 electron discharge device having within an evacuated container a plurality of anodes, a plurality of control electrodes, an electron emitting cathode, a tunable input circuit connected to said control electrodes, and a tunable output 50 circuit connected to said anodes, and a transmission line long relative to the working wave length coupling said input and output circuits of said device for controlling the frequency of operation thereof.

8. In apparatus for producing electrical oscillations comprising a cathode ray type of vacuum tube having a cathode, a plurality of control electrodes, and a plurality of anodes, means for suitably applying a negative potential to said 60 control electrodes and a positive potential to said anodes of the tube with respect to said cathode, tunable input and output circuits connected to said control electrodes and anodes, respectively, and means comprising a transmission line a multiple of a half wave length long on which standing waves are generated for regeneratively coupling the output and input circuits together whereby the frequency of the oscillations is held substantially constant.

9. An apparatus for producing electrical oscillations comprising a cathode ray type of vacuum tube having a plurality of control electrodes and a plurality of anodes, means for suitably applying a negative potential on said control 75

electrodes and a positive potential on said anodes of the tube with respect to the cathode, means to concentrate the electron stream emanating from the cathode, input and output circuits each 5 tuned to the frequency of the oscillations, means for regeneratively coupling the input and output circuits, and means independent of said output

circuit comprising a sharply tuned resonant transmission line circuit on which stationary waves are allowed to develop coupled to the input of said oscillator for stabilizing the frequency of the oscillations, and a utilization circuit coupled to said output circuit.

CLARENCE W. HANSELL.
